UNITED STATES PATENT OFFICE.

AARON D. PECK, OF JORDAN, NEW YORK.

WHEELBARROW.

SPECIFICATION forming part of Letters Patent No. 244,288, dated July 12, 1881.

Application filed May 17, 1881. (No model.)

To all whom it may concern:

Be it known that I, AARON D. PECK, of Jordan, in the county of Onondaga, in the State of New York, have invented new and useful 5 Improvements in Wheelbarrows, of which the following, taken in connection with the accompanying drawings, is a full, clear, and exact description.

This invention relates to the so-called "bolt-ed" or "knockdown" barrows, designed to be conveniently packed for transportation and set up on their arrival at their destination. The constituent members of such barrows are usually turned out after patterns in the factory, 15 and shipped in compact bundles to the consignees, who unite said members by means of carriage-bolts inserted through holes with which the several parts are provided. In setting up the said knockdown barrow for use 20 considerable difficulty has been experienced in properly uniting the constituent parts, owing to the frequent variations in the size of the trays made by the manufacturer, and also by the warping and shrinking thereof during their 25 transportation. The result has been that the tray had to be refitted and sprung or forced approximately into its requisite position on the barrow before it could be secured to the usual front and rear stays, the position of which was 30 fixed by the location of the bolt-holes in the handle to which said stays are attached.

It is to obviate the aforesaid difficulty which my invention has chiefly for its object, and to attain this I resort to the following construction: 35

The invention is fully illustrated in the annexed drawings, wherein Figure 1 is a side elevation of my improved wheelbarrow, and Fig. 2 is a transverse vertical section of same 40 on line xx .

Similar letters of reference indicate corresponding parts.

H represents the usual straight handle, extended the length of the barrow and having 45 journaled to its forward extremity the wheel W.

B B' are two braces bolted to the side of the handle and united at their foot to form the legs of the barrow. The rear brace, B, projects above the handle and forms thereby the 50 rear stay for the tray.

T denotes the tray, of the usual form, its rear end-board being secured to the extension of the brace B, as aforesaid, by means of bolts passing through the said parts, the forward

end-board being bolted to the forward stay, A, 55 which consists of a piece of board usually secured in a definite position on the handle H by carriage-bolts b b, inserted through certain holes a a provided in the said board and handle, the rear edge of said board being properly 60 shaped to receive the forward end-board of the tray, which is secured thereto by a bolt, c, as shown. In order to render the said stay adjustable, so as to accommodate trays of various sizes, and properly fit and sustain the same, I 65 provide the said stay A with a series of bolt-holes, a a, or an elongated hole or slot, for the reception of the bolts b, thus allowing said stay to be set up to the tray, instead of forcing the 70 tray to the stay.

Heretofore the tray was supported only by the handles H and the front and rear stays before described, said stays in some instances consisting in extensions of the legs of the barrow. The weight, therefore, came directly onto 75 the bolts which fasten the legs or braces B B' to the sides of the handle. In order to relieve said bolts to a great extent of the aforesaid strain, I terminate the brace B' back of the stay A and bring its extremity to abut 80 against the under side of the bottom board of the tray, thereby bringing the weight of the tray to bear directly on the end of said brace, as best seen in Fig. 2 of the drawings.

Having described my improvements, what 85 I claim is—

1. In combination with the handles H and tray T, the adjustable stay A, provided with slots or a series of bolt-holes, a a, and the bolts b, substantially as described and shown, 90 for the purpose set forth.

2. In combination with the handle H, provided with the stay A, and the tray T, resting on said handle and stay, the brace B', terminated back of the stay A and having its end 95 abutting against the under side of the bottom board of the tray, substantially in the manner and for the purpose shown and set forth.

In testimony whereof I have hereunto signed my name and affixed my seal, in the presence 100 of two attesting witnesses, at Syracuse, in the county of Onondaga, in the State of New York, this 12th day of May, 1881.

AARON D. PECK. [L. S.]
